BATTLE TANK STRUCTURE

William M. Sheehan, Philadelphia, and Samuel T. Wharton, Jr., Ridley Park, Pa., assignors to General Steel Castings Corporation, Granite City, Ill., a corporation of Delaware

Original application June 14, 1941, Serial No. 398,150. Divided and this application September 5, 1942, Serial No. 457,392

7 Claims. (Cl. 109—58.5)

This invention relates to battle tanks and more particularly to the construction adjacent to openings in the tank wall adapted to be closed by a door or the like. The application is a division of an earlier application by the same applicants filed June 14, 1941, Serial No. 398,150.

The main object of the invention is to arrange the tank wall and door so that the joint between the door and the wall will baffle the movement of metal splash tending to penetrate the joint, thus preventing the metal splash from entering the tank and injuring the men therein. It will be understood that the term "metal splash" includes metal in liquid form melted by the heat of impact of a projectile against the tank, or fragments of metal produced by shock, or combined molten metal and fragments.

This and other detail objects of the invention as will appear from the following description are attained by the structure illustrated in the accompanying drawing in which—

Figure 1 is a side elevation, partly diagrammatic, of a battle tank having a homogeneous armor plate wall provided with a door made in accordance with the present invention.

Figure 2 is a detailed vertical transverse section taken on the line 2—2 of Figure 1 and drawn to an enlarged scale with the intermediate portion of the structure broken away.

Figure 3 is a horizontal longitudinal section taken on the line 3—3 of Figure 1 and drawn to the same scale as Figure 2 and having the intermediate portion broken away.

The tank hull 1 preferably consists of a one-piece casting of armor steel having an exterior surface of general turtle back contour adapted to deflect projectiles striking it from any direction. The hull is mounted upon framework (not shown) which in turn is carried upon the supporting wheels 2 travelling over an endless track 3 in a manner well known in the art.

The upper portion of hull 1 is provided with a large opening over which is applied an inverted bowl-like turret 4 secured in place and other openings may be provided in the hull for guns, vision, etc. Men operating the tank will have entrance and egress through one or more doorways 5, each of which is fitted with a door 6. Preferably the door is of the swinging type and the door and wall are provided with integral hinge lugs 7 and 8 respectively, through which the hinge pin P is inserted. Other doors of similar construction may be provided on the tank,

such as, for instance, doors for gun openings, openings for vision, etc.

Each door includes a part 9 which projects well into the doorway, extending substantially from side to side and from top to bottom of the doorway. Surrounding doorway 5 is a flat rim 11 disposed to seat an opposing shoulder 10 on the door extending outwardly from part 9. Surrounding rim 11 is a channel-like recess 12 and spaced substantially from rim 11 is a flange or beading 13 on the wall projecting slightly from the normal contour of the wall. The door edge 15 projects beyond rim 11 up to, but clearing, the inner periphery of flange 13 and the inner face 16 of the door edge is spaced substantially from the bottom of recess 12 and from the outer face of flange 13, thus forming a pocket of substantial area with its inner end closed and with a narrow elongated entrance neck 14.

The marginal portion of the door is rounded as indicated at 17 so that the exterior surfaces of the door and wall flange 13 tend to merge as indicated by the broken line L in Figure 2. The joint described extends substantially continuously around the top, bottom and both sides of the door.

One side of the door opening is recessed as indicated at 18 (Figure 3) to receive a door lock latch (not shown) but this feature forms no part of the present invention.

The contour of the exterior marginal portion of the door and the adjacent exterior of flange 13, the restricted crevice 14 between the edge of the door and the opposing face of flange 13, and the relatively large recess 12 at the inner end of crevice 14 all cooperate to deflect, baffle and prevent the penetration of particles of metal or molten metal between the door and the door opening to the interior of the tank caused by impact of projectiles, and particularly of soft nose projectiles. The inwardly projecting portion 9 gives the door rigidity and, in the event of any warpage or bending of the door, provides an additional restricted passageway 19 which would interrupt or terminate the movement of particles of metal towards the interior of the tank.

It will be understood that the details of the joint may be changed without departing from the spirit of the invention, and the exclusive use of such modifications of the structure as come within the scope of the claims is contemplated.

What is claimed is:

1. In a battle tank, a wall provided with a door

opening, there being an outwardly facing flat surface on the wall forming a rim substantially surrounding said opening, a door fitting against said rim, and a flange projecting from the wall surface and substantially surrounding the edge of the door, said rim, flange and the marginal portion of the door forming a pocket with a closed inner end and a narrow entrance for resisting entrance to the tank interior of metal splash resulting from a projectile striking the tank exterior adjacent the joint between the door and the wall.

2. In a battle tank, a wall member having a door opening and a door member closing said opening, the joint between said members including a recess in one of said members facing the other of said members and extending around the opening, the latter-mentioned member having a portion seated against one edge of said recess and extending over the open side of said recess to form therewith a pocket to baffle the passage of metal splash through said joint caused by impact of a projectile near said joint.

3. In a battle tank, a wall member having a door opening and a door member closing said opening, a recess in one of said member's substantially surrounding said opening, the other of said members overlying one edge of said recess and approaching the other edge of said recess and being spaced substantially from the bottom of said recess intermediate said edges to form a trap in the joint between said members for baffling the passage of particles of metal splash through said joint when a projectile strikes the tank near said joint.

4. In a battle tank, a wall having a door opening defined by an outwardly facing rim, a door closing said opening and having a shoulder over-

lying said rim, said wall including a beading projecting outwardly of the face of the wall and beyond the plane of the face of said rim and the door shoulder and substantially surrounding the latter to deflect from the crevice between said rim and door shoulder particles of metal splash resulting from a projectile striking the tank.

5. Structure as described in claim 4 in which the door includes a part surrounded by its rim-engaging shoulder and projecting inwardly of the door opening beyond the plane of said rim a substantial distance and extending substantially from side to side and from top to bottom of the door opening so as to further baffle the passage of metal splash which may penetrate the crevice between the edge of the door and the rim.

6. Structure as described in claim 4 in which the body of the door projects outwardly beyond the plane of the outer face of the beading on the wall and the marginal portion of the door is rounded so as to merge with a contour line enclosing the beading and the door.

7. In a battle tank, a cast armor wall provided with a door opening, there being an outwardly facing surface on the wall substantially surrounding said opening and forming an opening rim, the wall being provided with a recess surrounding said rim and with a projection surrounding said recess and forming the outer edge thereof and extending outwardly beyond the face of said rim, a door having an inwardly facing portion fitting against said rim and an edge portion projecting beyond said rim and over said recess and spaced from the bottom thereof and terminating adjacent to the side of said projection forming the outer edge of said recess.
